Des. 240,869

Patented Aug. 3, 1976

240,869

ARTICLE STORAGE UNIT FOR AUTOMOTIVE VEHICLES

Charles R. Marr, 1855 E. Riverside Drive, Space 112,
Ontario, Calif. 91761

Filed May 31, 1974, Ser. No. 474,933

Term of patent 14 years

Int. Cl. D12—16

U.S. Cl. D87—1 R

Fig. 1.

Fig. 2.

Fig. 3.

Fig. 4.

FIG. 1 is a top plan view of an article storage unit for automotive vehicles, embodying my new design;

FIG. 2 is a right side elevational view with the cover of the rear compartment shown in a partially opened position, the opposite side being a mirror image thereof;

FIG. 3 is a rear elevational view; and

FIG. 4 is a front elevational view with the cover of the front compartment shown in a partially opened position.

I claim:

The ornamental design for an article storage unit for automotive vehicles, substantially as shown and described.
